(57) CLAIM

I claim the ornamental design for an ornament, as shown and described.

DESCRIPTION

FIG. 1 is a perspective view of an ornament with ribbon and with bell hanging in indentation in body of ornament showing my new design;

FIG. 2 is a left side view thereof;

FIG. 3 is a right side view thereof;

FIG. 4 is a front elevation view thereof;

FIG. 5 is a back elevation view thereof;

FIG. 6 is a top plan view thereof; and,

FIG. 7 is a bottom plan view thereof.

The broken lines in the drawings are environmental structure and form no part of the claimed design.

1 Claim, 3 Drawing Sheets
